UNITED STATES PATENT OFFICE.

WATSON R. SMITH, OF JACKSON, MICHIGAN.

SPRING STRUCTURE.

1,425,345.

Specification of Letters Patent. Patented Aug. 8, 1922.

Application filed January 18, 1922. Serial No. 530,044.

To all whom it may concern:

Be it known that I, WATSON R. SMITH, a citizen of the United States, residing at Jackson, in the county of Jackson and State 5 of Michigan, have invented new and useful Improvements in Spring Structures, of which the following is a specification.

This invention relates to spring structures.

10 Spring structures for automobile seats are generally built by manufacturers and sold without upholstering material applied to the structure. The purchaser of the spring structure applies an upholstered 15 covering thereto, or has it done by an upholsterer.

It is therefore one object of my invention to provide a spring structure to which the upholstering material may be readily applied 20 by an upholsterer or manufacturer of automobiles or the like.

Another object resides in the provision 25 of a spring structure embodying among other characteristics a simple and inexpensive base frame to which the supporting bars which support the body springs may be attached in any suitable manner, and to which the marginal edge of the skirt or upholstered covering may be readily secured 30 in position against undue wear or tearing and against accidental detachment incident to the rebound of the body springs subsequent to compression due to the weight of the rider, or because of uneven roadways.

35 With the above and other objects in view, the present invention consists in the combination and arrangement of parts as hereinafter more fully described and particularly pointed out in the appended claims, 40 it being understood that changes may be made in the form, proportion, size and minor details without departing from the spirit of the invention or sacrificing any of the advantages thereof.

45 In the drawings:

Fig. 1 is a fragmentary sectional view illustrating the invention with the marginal edge of the skirt in the groove ready to be secured therein.

50 Fig. 2 is a similar view, illustrating the skirt secured in the groove of the base frame.

Fig. 3 is a detail perspective view of a portion of the base frame.

55 Fig. 4 is a plan view of the base frame and spring supporting bars.

Fig. 5 is a detail perspective view of a portion of a modified form of base frame.

Referring now more particularly to the accompanying drawings, the reference letter 60 A indicates generally, a base frame, composed of sheet metal including spaced substantially vertical walls 6 and 7 and a web 8 connecting the upper longitudinal edges of the vertical walls. 65

The inner wall 7 has its lower edge directed inwardly and upwardly to provide a flange 9 forming an upwardly opening groove 10 in which the downwardly turned ends 11 of the spring supporting bars 12 70 are secured by pressing the upturned flange 9 toward the inner vertical wall 7 onto the downturned ends of said bars, as indicated at 13.

The outer wall 6 has its lower edge directed outwardly and upwardly, providing a flange 14, resulting in an outer groove 15 which opens upwardly, for a purpose presently explained.

Springs 16 are mounted on the supporting 80 bars 12, having their base coils clamped or pinched between the flanges of adjacent bars as shown at 17.

An upholstery covering 18 including a depending skirt 19 is mounted on the structure and the marginal edge of the skirt may have a cord, rope, wire, wood, a fibre strip or other character of spline wrapped or sewed therein.

The marginal edge of the skirt 19 is disposed in the aforesaid outer upwardly opening groove 15, and the flange 14 is then bent toward the outer vertical wall 6, without deflecting said vertical wall 6, to bind the marginal edge of the skirt in said groove 95 15 to hold the skirt from accidental disconnection from the base frame.

In Fig. 5 there is shown a modified form of the invention, the only difference between this and the other form described, 100 however, being that in the modified form, the inner groove 21 opens upwardly under the connecting web 8' and the ends of the spring supporting bars 12' are curled upwardly and inwardly and hook into the said 105 inner groove 21; otherwise, the two structures are the same.

What is claimed is:

1. In a spring structure, a base frame including spaced inner and outer substantially 110 vertical parallel walls having a connecting web between them, the walls being of sub-

stantially the same width and arranged in horizontal alinement, each wall at its lower edge having a flange cooperating with the respective wall to form a groove, said 5 grooves being arranged in horizontal alinement, spring supporting bars having their ends provided with hooks engaging in the groove adjacent the inner wall, springs mounted on said bars, and an upholstering 10 covering for the structure, including a skirt having its marginal edge disposed in the groove adjacent the outer wall, the flange adjacent the outer wall being bendable inwardly toward the outer wall on to the skirt 15 to secure the marginal edge of the latter to the base frame.

2. A base frame for spring structures composed of a continuous piece of sheet metal bent to form an inverted U-shaped strip including inner and outer substantially vertical walls connected together at their upper edges, the walls being of substantially the same width and arranged in horizontal alinement, each wall having a flange adjacent its lower edge to coact with the respective wall to form a groove adjacent each wall, the grooves being arranged in horizontal alinement. 20 25

In testimony whereof I have hereunto affixed my signature.

WATSON R. SMITH.
